Primary Examiner—Janice E. Seeger(74) *Attorney, Agent, or Firm*—Foley & Lardner**CLAIM**

The ornamental design for an end top for use with a playard, as shown and described.

DESCRIPTION

FIG. 1 is a perspective view of the end top for use with a playard of our new design mounted to a playard;
 FIG. 2 is a perspective view of the end top;
 FIG. 3 is a front elevation view thereof;
 FIG. 4 is a rear elevation view thereof;
 FIG. 5 is a top plan view thereof;
 FIG. 6 is a right side elevation view thereof, the left side elevation view being a mirror image of the right side elevation view; and,
 FIG. 7 is a bottom plan view thereof.
 The broken lines are for illustrative purposes only and do not form part of the claimed design.
